UNITED STATES PATENT OFFICE

EARL JACOBS, OF BROOKLYN, NEW YORK

DESIGN FOR A COMBINED BRIDGE BID INDICATOR AND CONTAINER

Application filed December 23, 1932. Serial No. 46,573. Term of patent 14 years.

To all whom it may concern:

Be it known that I, EARL JACOBS, a citizen of the United States, and residing in the borough of Brooklyn, county of Kings, and State of New York, have invented a new, original, and ornamental Design for a Combined Bridge Bid Indicator and Container, of which the following is a specification, reference being had to the accompanying drawing, forming a part thereof.

Figure 1 is a view showing in side elevation the combined bridge bid indicator and container for cigarettes, matches or ashes.

Figure 2 is a developed view illustrating the annular indicators bearing, respectively, the numbers and the card suits and relatively movable with respect to each other and the fixed inscription "Bid".

I claim:

The ornamental design for a combined bridge bid indicator and container substantially as shown and described.

This specification signed this 21st day of December, 1932.

EARL JACOBS.
